MACHINE LUBRICATOR

Folmar I. Bjerre, Hamburg, N. Y.

Application October 18, 1950, Serial No. 190,862

7 Claims. (Cl. 184—15)

1

This invention relates to machine lubricators, and more particularly to an improved lubricator of the type which is compressed air-operated to furnish a spray of lubricating oil intermittently to a point of desired lubricant application. For example, one useful application of the present invention is in connection with the lubrication of roller devices of moving trolleys or conveyors or the like; and by way of such example the drawing and specification herein illustrates and describes application of the invention to a conveyor lubricating arrangement whereby the constantly moving rollers and link pins may be lubricated without necessity of stopping the conveyor motion.

One of the objects of the present invention is to provide an improved lubricator system of the character described wherein the lubricant spray control valve is of improved form whereby to cause lubricant to be sprayed to the point of use in improved manner.

Another object of the invention is to provide a lubricator device of the character described, which is arranged to dispense successive blasts of lubricant spray to the desired point of use; said blasts being quantitatively predetermined and dispensed under control of a trigger actuated by a moving part without risk of continued spraying and emptying of the lubricant reservoir in event the moving device stops at such place as to hold the valve in its open position.

Another object of the invention is to provide a lubricator device of the character aforesaid which employs a functionally improved valve which is also structurally simplified and adapted for fool-proof operation.

Other objects and advantages of the invention will appear from the specification hereinafter.

In the drawing:

Fig. 1 is a fragmentary side elevation of a travelling conveyor or trolley, showing a lubricator of the present invention arranged in conjunction therewith for intermittent operation, controlled to synchronize with arrivals of the conveyor rollers and link pins at the lubricating stations for spraying the parts with lubricant;

Fig. 2 is a fragmentary sectional view, on an enlarged scale, through the spray control valve device of Fig. 1;

Fig. 3 is a fragmentary section taken along line III—III of Fig. 2;

Fig. 4 is a fragmentary section, on an enlarged scale, taken along line IV—IV of Fig. 1;

Fig. 5 is a section, taken on an enlarged scale along line V—V of Fig. 1;

2

Fig. 6 illustrates a modified form of the construction of Fig. 3; and

Fig. 7 is a fragmentary section taken along line VII—VII of Fig. 1.

As shown in the drawing, a travelling conveyor mechanism is illustrated to include a support rail 10 having flanges 12 upon which run rollers 14 which are connected by pins 15 to stirrups 16 carrying the conveyor strand which in this case is illustrated to comprise a link chain illustrated generally at 17. The chain links are interconnected by pins 18; and thus it will be appreciated that the conveyor is of the type such as from time to time requires lubrication of the roller pins 15 and the link pins 18. The lubricator device of the invention is illustrated as being mounted upon the stationary rail 10, as by means of a base plate 19, which of course might alternately be arranged to span a pair of parallel rails in the case of a dual rail conveyor. The lubricator device includes a compressed air supply conduit 20; a shut-off valve 21; an air filter 22 which may be of any suitable construction so as to be adapted to segregate liquid or solid impurities present in the compressed air supply. From the filter 22 the compressed air passes through a pressure regulator 24 from whence it is delivered through a conduit into an inspirator 25 which is mounted in connection with an oil supply tank 26. As illustrated in more detail in Fig. 4, the inspirator device 25 includes a suitably sized bore 27 therethrough in communication with the conduit 20 and a suction channel 28 in communication therewith. The channel 28 is in communication with a tube 29 which extends into the tank 26 and almost to the bottom thereof, whereby rush of air through the bore 27 causes the inspirator device to pick up a supply of lubricating oil and mixes it with the air and delivers it in fog form through a discharge conduit 30 which leads to the intake port of the control valve 31.

As illustrated in Fig. 1, the valve 31 includes a second port 32 arranged in communication with a cylinder 34 which contains a floating piston or moving diaphragm as indicated at 35. At its other end the cylinder 34 is connected in series with an air pressure reservoir tank 36 which is also in series with a pressure release valve 38; a pressure regulator 39; and thence into connection as indicated at 40 with the compressed air supply conduit 20, all for purposes to be described hereinafter.

The flow control valve 31 is illustrated in Figs. 2-3 as comprising a body portion 42 which is centrally bored to accommodate in longitudinally free

sliding relation therein a valve spool 44. The spool 44 is longitudinally bored as indicated at 46 part way of its length, and is exteriorly grooved as indicated at 48-50; the grooves 48-50 being each arranged in communication with the central bore 46 as by means of transverse bores 51-52. The body portion 42 is supplemented by a valve base piece 54 which is bored as indicated at 56 in alignment with the bore 46 of the body member 42, and is also formed with a passageway 58 comprising the inlet port of the valve device to which is connected the conduit 30 referred to hereinabove.

As stated hereinabove, the valve body is also formed with a second port connection 32 which communicates with the body bore, and as illustrated in Fig. 2, an outlet port is provided in the valve body in communication with the central bore as indicated at 59 for connection with the lubricant delivery tube 60. The body member 42 is counterbored to a slightly larger diameter as indicated at 62 (Fig. 2), and is recessed at its lower end to positionally accommodate an O-ring seal 64 which also bears against the base plate 54 for positional retention; the spool 44 being formed to reduced diameter at its lower end as indicated at 66. The spool is also grooved as indicated at 67 to accommodate an O-ring seal 68, and is grooved at 69 to provide an enlarged air chamber interiorly of the valve bore in communication with the port connection 32. The valve spool groove and body port parts are so dimensioned and relatively arranged that whenever the valve spool is in its non-dispensing position as illustrated in Fig. 2, communication for pressure is provided through the inlet port 58 into the bottom bore 56 and thence between the reduced spool portions 66 and the O-ring 64, to the inner bore 62. Communication for pressure passes thence through the groove 69 to the second port connection 32, while being sealed by the O-ring 68 from passage therebeyond. Thus, under this condition oil-air mixture from the inspirator 25 is permitted to flow through the inlet port 58 and the second port connection 32 into one end of the cylinder 34 so as to thereby bias the floating member 35 against pressure previously established in the reservoir 36 and the conduit system connected thereto. Thus, the cylinder 34 will be loaded with oil-air mixture; the regulator 39 having been previously set to a pressure somewhat lower than the pressure in the conduit 20 so that the back pressure in the reservoir 36 against the cylinder 34 will be somewhat less than the pressure ahead of the floating member 35. Thus, when the valve 31 is actuated to dispensing position the supply pressure against the movable piston wall 35 is cut off and the valve dispensing port opened, whereupon the pressure behind the piston wall 35 as furnished by the reservoir 36 will be free to push the piston wall 35 toward chamber emptying position. Thus the cylinder 34 with its floating member 35 and the reduced air pressure reservoir 36 comprise a charge metering and dispensing accumulator wherein a substantially constant dispensing force is applied to the charge of air-oil mixture in the cylinder 34 by the air in the reservoir 36. This results in a more uniformly high pressure nozzle dispensing operation, which provides shorter and more accurate blasts of lubricant at the parts to be lubricated.

Incidentally, while the spool 44 is in the non-dispensing position thereof shown in Fig. 2, the air pressure at the port connection 58 operates against the bottom end of the spool to bias the 75

latter upwardly so as to retain it in the non-dispensing position illustrated. However, forcible displacement of the spool 44 downwardly from the position shown in Fig. 2 will cause the body portion of the spool 44 to engage in fluid-sealing contact with the O-ring 64 so as to thereby cut off the entrance of oil-air mixture from the inlet 58. Then for a slight travel distance both O-rings 64-68 are engaged to seal all ports, following 10 which the O-ring 68 is brought down so as to register with the enlarged bore portion 62 of the valve body whereupon it ceases to function as a sealing medium and permits oil-air mixture from the cylinder 34 to return through the port connection 32 and to flow into the spool groove 50. From thence it passes into the central bore 46 and thus the oil-air mixture is free to gain access through the transverse bore 51 into the dispensing tube 60 for dispensing purposes, as will be explained more fully hereinabove.

The valve body portion 42 is transversely bored in communication with the upper end of the inner longitudinal bore thereof to receive in rotatable relation therein a cam shaft 70 which is formed 25 with a flatted portion 72 registering with the top end of the spool 44; the spool and cam parts being so dimensioned and relatively arranged that when the cam shaft 70 is in the position thereof shown in Figs. 2 and 3 the spool 44 is free to assume the non-dispensing position thereof as indicated in Fig. 2. However, upon rotation of the cam shaft it will force the spool 44 to move downwardly against the air pressure forces at the lower end thereof and to the dispensing position 30 thereof as described hereinabove.

The cam shaft 70 is pressure sealed in relation to the body 42, as by means of any suitable seals as indicated at 74, and is fitted with an actuating arm device as indicated at 75. The actuating arm 40 75 is arranged to extend as illustrated in Fig. 1 to come into bearing rotating contact with moving portions of the machine to be lubricated; and as in the case of the present illustration the arms 75 are arranged to come into rotating contact with the stirrups 16 which suspend the conveyor chain from the rollers 14. Thus, as illustrated in Fig. 2, the valve and actuating parts thereof are so arranged that in between periods of contact the actuator arm 75 will be disposed to extend straight downwardly, and during contact periods the arm 45 will be actuated to rotate counter-clockwise, as shown in the drawing as to the position thereof shown in Fig. 1, at which time the control valve 50 will be thereby displaced into dispensing position.

Thus, the lubricant will then be delivered through the tube 60 which may be conveniently connected into a branch tube 80 carrying nozzles 82 for jetting lubricant fog onto the conveyor link pins, as shown in the drawing. Thus, when the valve spool 44 is in dispensing position, the lubricant fog previously stored in the cylinder 34 will be thereupon dispensed in response to the pressure forces from the reservoir 36 and its connected system; whereby the lubricant charge will be jetted against the parts to be lubricated. 55 It is a particular feature of the arrangement of the invention as shown and illustrated hereinabove that the pressure forces within the reservoir 36 operate automatically to pressure the lubricant fog out through the nozzles 82 rapidly and completely without substantial undesirable falling off of actuating pressure toward the end of the operation such as would otherwise permit the last of the lubricant to slowly flow out of the nozzles ineffectively for the intended purpose.

As illustrated in Fig. 6, the cam shaft 70 may be longitudinally bored as indicated at 84 and transversely bored as indicated at 86 so as to communicate the bore 84 with the bore 46 of the valve spool 44. Then, by means of connections 87 (Figs. 1 and 5) the bored cam shaft may be fluid-connected to lubricant dispensing tubes 88 which terminate in nozzles 89 directed toward the bearing devices of the rollers 14 when the actuating arm 75 is contacted by the moving stirrup of the conveyor; the arms 75 and the tubes 88 being bracketed together as indicated at 90 so as to swing together to follow the motion of the conveyor parts during the lubricant dispensing cycle.

As shown in Figs. 1 and 7, the nozzles 82 may be arranged for positional adjustments in any direction by mounting the branch tube 80 in brackets 94 which are in turn mounted for either vertical or side-wise adjustments at their upper ends upon a cross bar 95 which is in turn vertically and longitudinally adjustably carried upon a pair of stirrups 96 which mount by means of adjustable connections 97 upon the base plate 19 previously referred to. Thus, it will be appreciated that by simple adjustments of the cross bar and bracket devices 94-95 the nozzles 82 may be readily adjusted to various positions so as to be suited to dispense lubricant to any desired point on the moving machine while the delivery tubes 88 may be suitably bent so as to direct the nozzles 89 thereof to dispense lubricant in any desired manner.

Thus, it will be appreciated that a particular feature of the present invention is that at no time is there through passage from conduit 30 to dispensing conduit 60 (Fig. 2) and that the valve operates alternately to pre-load the charging cylinder 34 which subsequently is discharged through the same valve device to the dispensing points upon opening of the valve. Thus, a pre-determined charge of lubricant is dispensed as needed in an improved manner. Also, if the valve is held in open position, such as by stopping of the conveyor mechanism, it cannot possibly operate to hold open the line between the inspirator 25 and the dispensing nozzles, such as would otherwise cause oil and air to continue to blow upon the stopped machine.

Whereas, the drawing and description hereinabove has included reference to the employment of an accumulator wherein the dispensing charge metering chamber is in the form of the cylinder 34 and floating piston 35, it will be appreciated that it is not necessary to employ such a device and that the second port 32 of the valve member may be simply directly connected to the reservoir device 36 as an accumulator. In such event there would be no pressure release valve 38 or pressure regulator 39, and no connecting conduit system leading out of the reservoir 36 would be required as illustrated in Fig. 1; the reservoir 36 functioning only as a pressure accumulating bell or chamber to provide pressure for forcing the lubricant to return through the valve and to the dispensing points when the valve spool 44 is shifted to dispensing position. Thus, in this instance there would be no likelihood of undesirable bleeding of the main supply system as explained hereinabove. Thus in either form of the invention the charge of air-oil mixture is stored in an accumulating chamber for being subsequently dispensed therefrom by the pressure forces therein.

It will be appreciated that the oil feed control and the air pressure control and the trigger

contact devices are readily adjustable to suit the lubricator device of the invention to various conditions of operation, and that it is a particular feature of the invention that the compressed air and oil supply is automatically shut off in event of stoppage of the moving device in a position of trigger contact. Also, in view of the fact that the device automatically dispenses only a predetermined quantity in response to each trigger contact, only the desired amount of air and oil will be dispensed at any particular point; and this feature is particularly advantageous for example in connection with slow moving conveyors or like machines. Still another particular advantage of the invention is that reverse direction operation of the conveyor or other machine to be lubricated will not cause injury either to the conveyor or lubricator parts because the trigger devices of the lubricator operate the same in both directions and can be arranged so that no lubricant will be dispensed incidental to reverse direction operation of the conveyor. Thus, these features and advantages along with other features mentioned hereinabove constitute important advantages in the art; and although only one form of the invention has been shown and described in detail it will be apparent to those skilled in the art that the invention is not so limited but that various changes may be made therein without departing from the spirit of the invention or the scope of the appended claims.

I claim:

1. In a lubricating device, means for supplying air-oil mixture under pressure, and means for conducting the air-oil mixture from said supply means to a dispensing nozzle directed at the part to be lubricated comprising a pressure accumulating chamber, valve means intercalated in said conducting means intermediate of said supply means and said nozzle, said valve means including a body portion and a member movable therein in reverse directions between dispensing and non-dispensing positions, said member being biased to move to non-dispensing position by the pressure from said supply and constructed and arranged to thereupon permit flow of oil-air mixture through said valve into said accumulating chamber, said valve member being adapted to be forcibly displaced against the action of the pressure thereon from said supply means to be moved thereby to dispensing position whereupon said valve member operates to cut off the supply pressure and disposes said accumulating chamber in open communication with said dispensing nozzle, and valve actuating means comprising a member disposed to register in bearing relation against a moving part of the machine to be lubricated to be actuated by movement thereof so as to forcibly displace said valve member against the pressure thereon into dispensing position whereupon the charge of oil-air within said accumulating chamber will be dispensed through said nozzle.

2. In a lubricating device, means for supplying air-oil mixture under pressure, and means for conducting the air-oil mixture from said supply means to a dispensing nozzle directed at the part to be lubricated, said conducting means comprising an accumulating chamber and three-way valve means intercalated in said conducting means intermediate of said supply means and said nozzle, said valve means including a bored body portion and a spool valve member movable therein in reverse directions between dispensing and non-dispensing positions, said

member being biased to move to non-dispensing position by the pressure from said supply and constructed and arranged to thereupon cut off flow to said nozzle and to permit flow of oil-air mixture from said supply through said valve into said accumulating chamber, said valve member being adapted to be forcibly displaced against the action of the pressure from said supply to be moved to dispensing position whereupon said valve member operates to cut off the supply pressure and disposes said accumulating chamber in open communication with said dispensing nozzle, and valve actuating means comprising a member disposed to register in bearing relation against a moving part of the machine to be lubricated to be actuated by the movement thereof so as to forcibly displace said valve member against the pressure thereon into dispensing position whereupon the charge of oil-air within said accumulating chamber will be 20 dispensed through said nozzle.

3. In a lubricating device, means for supplying air-oil mixture under pressure, conduit means for conducting the air-oil mixture from said supply means and to a dispensing nozzle directed at the part to be lubricated, three-way valve means intercalated in said conduit means intermediate of and thereby connected to said supply means and said nozzle, an accumulating chamber connected to said valve, said valve means including a body portion and a member movable therein between dispensing and non-dispensing positions, said member being moved to non-dispensing position by the pressure from said supply and constructed and arranged to thereupon permit flow of oil-air mixture through said valve into said accumulating chamber, said valve member being adapted to be forcibly displaced against the action of said pressure to move to dispensing position whereupon said valve member operates to cut off the supply pressure and disposes said accumulating chamber in open communication with said dispensing nozzle, and valve actuating means comprising a member disposed to register in bearing relation against a moving part of the machine to be lubricated to be actuated by the movement thereof so as to forcibly displace said valve member against said pressure into dispensing position whereupon the charge of oil-air within said accumulating chamber will be dispensed through said nozzle.

4. In a lubricating device, means for supplying air-oil mixture under pressure, and means for conducting the air-oil mixture from said supply means to a dispensing nozzle directed at the part to be lubricated comprising a pressure accumulating chamber, valve means intercalated in said conducting means intermediate of said supply means and said nozzle, said valve means including a body portion and a valve member movable therein between dispensing and non-dispensing positions, said member being moved to non-dispensing position by the pressure from said supply and constructed and arranged to thereupon cut off flow to said nozzle and to permit flow of air-oil mixture from said supply through said valve into said accumulating chamber, said valve member being adapted to be forcibly displaced against the action of said pressure to move to dispensing position whereupon said valve member operates to cut off the supply pressure and disposes said accumulating chamber in open communication with said dispensing nozzle, and valve actuating means com-

10
15

prising a member disposed to register in bearing relation against a moving part of the machine to be lubricated to be actuated by the movement thereof so as to forcibly displace said valve member against said pressure into dispensing position whereupon the charge of oil-air, within said accumulating chamber will be dispensed through said nozzle, said accumulating chamber having a movable wall portion normally biased toward chamber loading position by the action of said supply pressure thereon, and reduced pressure pneumatic pressure means connected to said supply means and operable to move said wall portion toward chamber emptying position upon release of the action of said supply pressure against said wall portion.

5. In a lubricating device, means for supplying air under pressure, and means for conducting the air from said supply means to a dispensing nozzle directed at the part to be lubricated, said conducting means comprising an accumulating chamber and valve means intercalated in said conducting means intermediate of said supply means and said nozzle, said valve means including a body portion and a valve member movable therein between dispensing and non-dispensing positions, said member being moved to non-dispensing position by the pressure from said supply and constructed and arranged to thereupon permit flow of air through said valve into said accumulating chamber, said valve member being adapted to be forcibly displaced against the action of said pressure to move to dispensing position whereupon said valve member operates to cut off the supply pressure and disposes said accumulating chamber in open communication with said dispensing nozzle, and valve actuating means comprising a member disposed to register in bearing relation against a moving part of the machine to be lubricated to be actuated by the movement thereof so as to forcibly displace said valve member against said pressure into dispensing position whereupon the charge of air within said accumulating chamber will be dispensed through said nozzle, said accumulating chamber having a movable wall portion normally biased toward chamber loading position by the action of said supply pressure thereon, means connected to said supply means and operable to move said wall portion toward chamber emptying position upon release of the action of said supply pressure against said wall portion, and oil supply means including inspirator means connected to said conducting means and adapted to introduce oil into the air passing through said conducting means for being carried thereby as an air-oil mixture to said dispensing nozzle.

6. In a lubricating device, means for supplying air-oil mixture under pressure, and means for conducting the air-oil mixture from said supply means to a dispensing nozzle directed at the part to be lubricated comprising an accumulating chamber, valve means intercalated in said conducting means intermediate of said supply means and said nozzle, said valve means including a member movable between dispensing and non-dispensing positions, said member being normally disposed in non-dispensing position and constructed and arranged to thereupon permit flow of oil-air mixture through said valve into said accumulating chamber, said valve member being adapted to be forcibly displaced to move to dispensing position whereupon said valve member operates to cut off the supply pressure and disposes said accumulating chamber in open

70

75

communication with said dispensing nozzle, and valve actuating means comprising a member disposed to register in bearing relation against a moving part of the machine to be lubricated to be actuated by the movement thereof so as to forcibly displace said valve member into dispensing position whereupon the charge of oil-air within said accumulating chamber will be dispensed through said nozzle, said accumulating chamber having a movable wall portion normally biased toward chamber loading position by the action of the pressure from said supply thereon, and substantially constant force means operable to move said wall portion toward chamber emptying position upon release of the action of said supply pressure against said wall portion.

7. In a lubricating device, means for supplying air-oil mixture under pressure, conduit means for conducting the air-oil mixture from said supply means and to a dispensing nozzle directed at the part to be lubricated, an accumulating chamber, a three-way valve means intercalated in said conduit means intermediate of said supply means and said nozzle, said valve means having a first port connected to the supply by said conduit means and a second port connected to said accumulating chamber and a third port connected to said nozzle by said conduit means, said valve means including a body portion and a spool valve member movable therein in reverse directions between dispensing and non-dispensing positions, said member being moved to non-dispensing position by the pressure from said supply and

constructed and arranged to thereupon cut off flow to said nozzle through said third port and to permit flow of oil-air mixture from said supply through said first port and out through said second port of said valve into said accumulating chamber, said valve member being adapted to be forcibly displaced against the action of said pressure to move to dispensing position whereupon said valve member operates to cut off the supply pressure beyond said first port and disposes said accumulating chamber in open communication with said dispensing nozzle, through said second and third ports, and valve actuating means comprising a member disposed to register in bearing relation against a moving part of the machine to be lubricated to be actuated by the movement thereof so as to forcibly displace said valve member against said pressure into dispensing position whereupon the charge of oil-air within said accumulating chamber will be dispensed through said nozzle.
